UNITED STATES PATENT OFFICE.

CONRAD M. CONRADSON, OF MADISON, WISCONSIN, ASSIGNEE TO MADISON MACHINE COMPANY, OF MADISON, WISCONSIN, A CORPORATION OF WISCONSIN.

SPEED-VARIATOR.

1,035,860.

Specification of Letters Patent. Patented Aug. 20, 1912.

Application filed November 12, 1910. Serial No. 591,932.

To all whom it may concern:

Be it known that I, CONRAD M. CONRADSON, a citizen of the United States, and a resident of Madison, in the county of Dane and State of Wisconsin, have invented a new and Improved Speed-Variator, of which the following is a specification.

This invention pertains to means for varying, as desired, the relative speeds or rates of rotation of a driving and a driven shaft and relates more especially to that class of such mechanisms in which there are provided on each shaft two cone pulley sections or disks with their apexes facing each other and with such pulley sections on each shaft movable relatively to and from each other longitudinally of the shaft. In such structures the motion is transmitted from one shaft to the other by a belt engaging and wedging between the pulley sections on each shaft, the structure of the belt being preferably adapted to such wedging action. For varying the relative speeds of the shafts the pulley sections are moved toward each other on one shaft and correspondingly apart on the other shaft.

The object of my present invention is to provide mechanism operated by fluid pressure, preferably hydraulic, for actuating the pulley sections toward and from each other on the shafts and with the thrust exerted by such mechanism sustained entirely in the way of a longitudinal stress upon the shafts or members carried thereby. As an illustration of such fluid pressure actuated mechanism I have shown and described hydraulically operated mechanism.

The accompanying drawings showing only diagrammatically a mechanism of the character and for the purpose described are as follows,—

Figure 1 is a plan view of the mechanism. Fig. 2 is a side view of the pulleys or wheels only of such a mechanism adjusted to effect a substantially equal rate of rotation for both of the shafts, the belt being indicated in the position for securing such result. The standards or hangers for supporting the shafts are shown in side view. Fig. 3 shows the shafts in vertical transverse section and with the wheels or pulleys thereon adjusted to approximately a maximum difference of relative rotation between the shafts, the belt being shown in position for securing such result. Fig. 4 is a transverse vertical sec-

tion through approximately the center of the controlling valve of the mechanism. Fig. 5 is a longitudinal section taken diametrically through the center of one of the shafts and the mechanism carried thereby. Fig. 6 shows in plan view a detail of the connecting means between one of the conical pulley sections and its actuating mechanism. Fig. 7 is a transverse sectional view of the hub of one of the wheels taken on the line $x-y$ of Fig. 5. Fig. 8 is a diagrammatic view of a modified mechanism for actuating the conical pulley sections on the shafts showing the cylinder of such mechanism partially in section.

Throughout the several views of the drawings similar parts are designated by similar reference characters.

Referring to the drawings,—for supporting the shafts in my speed variator I make use of connected hangers or standards T^2 , such as shown in Figs. 1 and 2, and in which T are connecting girders and T^1 are inclosing casings for the bearings E adjustably secured therein by means of the adjusting bolts e threaded through the bosses t . The standards T^2 have foot pieces, which may be connected as seen at T^3 . The shafts are indicated at S and S^1 , either one of which may be supposed to be the driven and the other one the driving shaft. For actuating the movable one of the pair of conical pulley sections on each of these shafts I may employ any preferred mechanism for connecting such pulley sections with the movable member of a hydraulically actuated mechanism preferably a piston operating in a cylinder.

In the accompanying drawings I have shown one form of such a mechanism in which the shafts S and S^1 are tubular and are revolvably supported in the bearings E in the usual way. On the shaft S is seen a disk D^1 provided with a hub d^1 through which is threaded the bolt n for securing the disk D^1 on the shaft S against angular or longitudinal movement. On this shaft S there is also seen a similar disk D but longitudinally slideable thereon and actuated longitudinally of such shaft by means of the mechanism now to be described, reference being had more especially to Fig. 5. This shaft S is tubular and the wall thereof is provided, near the center of the shaft, with slots s opening outwardly from the bore

thereof and through which there engages the actuating bar O extending outwardly also through slots provided therefor in the hub d of the disk D and secured in such hub 5 so as to carry the disk D therewith by means of bolts o threaded into the hub d and the bar O as clearly indicated in Figs. 5 and 7. This bar O extends through and is rigidly secured in the left hand end of the piston rod P slidable in the bore of the shaft S and guided therein by means of the enlarged portion p seen at the left hand end and in which is secured the bar O , while the main portion of the rod P is reduced in diameter 10 as indicated so as to freely slide within the tubular shaft S .

The right hand end s^1 of the shaft S is threaded and has secured thereon a cylinder A held against angular movement by the 20 set screw a^2 , and within this cylinder there is slidably fitted the piston head P^1 . The cylinder A is provided at its center with a stuffing box a having threaded thereover a follower a^1 of the usual construction in order that a fluid tight joint may be made between the head of the cylinder A and the fixed supply pipe v^{11} permitting the rotation of the cylinder A . The shaft S^1 has similarly supported thereon the 30 fixed disk C^1 carrying a hub c^1 and secured in place by means of a bolt n while the disk C has a hub c , and secured in the slot therein by means of bolts o is seen the bar O secured in the right hand end of a piston rod 35 exactly like the rod P , the left hand end of which, with reference to Fig. 1, carries a piston head, not seen, but working within the cylinder B , also having a head and a stuffing box b at its center and threaded 40 thereover the follower b^1 , the structure being in all respects the same as that already described for the shaft S with reference to Fig. 6.

By means of the stuffing box b there is 45 maintained a fluid tight joint between the cylinder head and the pipe v of a character permitting the rotation of the cylinder. The cylinder B is connected through the system of piping v , v^1 and v^2 with a valve 50 chamber H , while the cylinder A is similarly connected through a similar system of piping v^{11} , v^{10} and v^9 with the valve chamber H . The valve chamber H is provided with bosses h and h^2 within which there is secured the pipes v^2 and v^9 . The chamber H is also provided with bosses h^1 and h^3 in which are secured respectively the pipes v^3 and v^8 . This chamber H is connected with one side of a pump U through the system 60 of piping v^8 , v^7 and v^6 and to the other side of the pump U through the system of piping v^5 , v^4 and v^1 .

Referring now to Fig. 4,—the valve 65 chamber H has therein the rotatable valve G having ducts therethrough g and g^1

adapted, when operating handle N thereof is in the position indicated in full lines in Fig. 4, to connect the pipes v^2 and v^8 together and to similarly connect the pipes v^3 and v^9 together, while when such valve is 70 rotated over to the right, by the handle N causing the same to assume the position indicated at N^1 in dotted lines, the duct or passage g assumes the position indicated at g^2 connecting the pipes v^2 and v^8 and similarly the duct g^1 assumes the position indicated at g^3 in dotted lines connecting the pipes v^3 and v^9 . The pump U is provided with an operating handle U^1 and the usual piston and piston rod, the outer end of 75 which articulates with the handle U^1 as seen at u while the lower end of the handle articulates with one end of the link u^1 , the other end of which latter articulates with an ear u^2 carried by the pump U . The 80 pump U is of substantially the usual construction provided with a check valve preventing the return therethrough of water from the pipe v^8 and also a check valve preventing a return from the pump of 85 water into the pipe v^5 , whereby the circulation caused by the pump when operated is always in the direction indicated by the full arrows. The result of this is that the circulation through the system of piping 90 v^3 , v^4 and v^5 , the pump U and piping v^6 , v^7 and v^8 is always in the direction indicated by the full arrows, and with the handle N in the position indicated in full lines, the operation of the pump draws the 95 water from the cylinder B and forces the same into the cylinder A forcing the disk D to the left permitting the disk C to move to the left as it is acted upon by the transmission belt indicated at R in Figs. 2 and 3. 100 When the handle N is moved over to the right to the position indicated at N^1 in Fig. 4 the operation of the pump draws the water from the cylinder A and forces the same into the cylinder B and effects a reverse operation 105 of the disks C and D , and in this case the direction of the flow through the piping v^{11} , v^{10} , v^9 , v^2 , v^1 and v is indicated by the half arrows in Fig. 1. Thus it will be seen 110 that the position of the valve handle N determines the directions of the movements of the disks C and D effected by the operation 115 of the pump U and correspondingly the relative rates of rotation of the shafts carrying such disks. It will also be readily 120 understood that the entire thrust exerted both in adjusting the relative position of the disks against the belt and also the thrust exerted by the belt itself on the disks tending 125 to separate them is received in the way of a longitudinal tension on the shafts S and S^1 reducing the necessary weight of the parts to a minimum. The disks C , C^1 , D and D^1 may preferably be provided with 130 ribs r extending radially outward from the

hubs thereof for stiffening the cone surfaces of such disks.

Refer now to Fig. 8. This figure shows a modified mechanism for actuating the pistons P and P¹. In this arrangement I make use of a cylinder M suitably mounted on the base M¹ and having therein the piston m secured on the hollow piston rod j² within which there is threaded the operating screw j having secured on its upper end the operating wheel J. This screw j has a bearing in the upper end of an upwardly extending arm M² of a character to permit rotation but to prevent longitudinal movement thereof within such bearing as indicated in dotted lines. From the cylinder M there extend leads k and k¹ which may contain valve chambers with suitable valves therein having connected to the stems thereof the levers k² and k³ connected to work together by means of a link K articulating therewith. To the valved connections k and k¹ there are secured the pipes v and v¹. The operation of this modification is as follows:—The piston m is moved in either direction in the cylinder M according to the direction of rotation imparted to the operating wheel J and accordingly the fluid on one side of the piston m is forced outwardly into one of the cylinders A or B and a corresponding amount of fluid from the other cylinder is permitted to pass through the pipe connecting the same with the cylinder M on the other side of the piston m. The operation of the lever k² cuts off, when desired, communication between the cylinder M and the cylinders A and B in the manner clearly indicated. By the use of this modification of the actuating mechanism the action of the pistons is rendered more uniform and any possible disadvantage resulting from the pulsating action of the mechanism hereinbefore described is entirely removed.

It is believed from the foregoing description of the construction and operation of the several features of my speed variator that the method of using the same is sufficiently clear to call for no further explanation herein.

50 What I claim is:

1. In a device for the purpose described, in combination with the two shafts, a pair of relatively movable coned pulley sections on each shaft; for each movable coned pulley section and operatively connected therewith, a separate reservoir containing fluid under pressure and means, exerting a longitudinal stress on the shafts, for effecting inverse relative movements between the pulley sections on the shafts comprising means for varying inversely the volumes of fluid in the reservoirs.

2. In a device for the purpose described, in combination with the two shafts, a pair

of relatively movable coned pulley sections 65 on each shaft; for each movable coned pulley section and operatively connected therewith, a separate reservoir containing fluid under pressure and means, exerting a longitudinal stress on the shafts, for effecting 70 simultaneous inverse relative movements between the pulley sections on the shafts comprising means for varying simultaneously and inversely the volumes of fluid in the reservoirs.

3. In a device for the purpose described, in combination with the two shafts, a pair 75 of relatively movable coned pulley sections on each shaft; for each movable coned pulley section and operatively connected therewith, a separate reservoir containing fluid under pressure and means for effecting inverse relative movements between the pulley sections on the shafts comprising means for varying inversely the volumes of fluid in the 80 reservoirs.

4. In a device for the purpose described, in combination with the two shafts, a pair 90 of relatively movable coned pulley sections on each shaft; for each movable coned pulley section and operatively connected therewith, a separate reservoir containing fluid under pressure and means for effecting simultaneous inverse relative movements between the pulley sections on the shafts comprising 95 means for varying simultaneously and inversely the volumes of fluid in the reservoirs.

5. In a device for the purpose described, in combination with the two shafts, a pair 100 of relatively movable coned pulley sections on each shaft; for each movable coned pulley section and operatively connected therewith, a separate reservoir containing fluid under pressure; means, exerting a longitudinal stress on the shafts, for effecting inverse relative movements between the pulley sections on the shafts comprising means for varying inversely the volumes of fluid in the reservoirs and members operatively connecting the movable pulley sections with the reservoirs adapted to sustain by longitudinal stress the thrust exerted by the inverse relative movement effecting means.

6. In a device for the purpose described, 115 in combination with the two shafts, a pair of relatively movable coned pulley sections on each shaft; for each movable coned pulley section and operatively connected therewith, a separate reservoir containing fluid 120 under pressure; means, exerting a longitudinal stress on the shafts, for effecting simultaneous inverse relative movements between the pulley sections on the shafts comprising means for varying simultaneously and inversely the volumes of fluid in the reservoirs and members operatively connecting the movable pulley sections with the reser-

- voirs adapted to sustain by longitudinal stress the thrust exerted by the inverse relative movement effecting means.
7. In a device for the purpose described, in combination with the two shafts, a pair of relatively movable coned pulley sections on each shaft; for each movable coned pulley section and operatively connected therewith, a separate reservoir containing fluid under pressure; means for effecting inverse relative movements between the pulley sections on the shafts comprising means for varying inversely the volumes of fluid in the reservoirs, and members operatively connecting the movable pulley sections with the reservoirs adapted to sustain by longitudinal stress the thrust exerted by the inverse relative movement effecting means.
8. In a device for the purpose described, in combination with the two shafts, a pair of relatively movable coned pulley sections on each shaft; for each movable coned pulley section and operatively connected therewith, a separate reservoir containing fluid under pressure; means for effecting simultaneous inverse relative movements between the pulley sections on the shafts comprising means for varying simultaneously and inversely the volumes of fluid in the reservoirs and members operatively connecting the movable pulley sections with the reservoirs adapted to sustain by longitudinal stress the thrust exerted by the inverse relative movement effecting means.
9. In a device for the purpose described, in combination with the two shafts, a pair of relatively movable coned pulley sections on each shaft; for each movable coned pulley section and operatively connected therewith, a separate cylinder containing fluid under pressure and a piston movable in the cylinder and means, exerting a longitudinal stress on the shafts and permitting rotation thereof, for effecting inverse relative movements between the pulley sections on the shafts comprising means for varying inversely the volumes of fluid in the cylinders.
10. In a device for the purpose described, in combination with the two shafts, a pair of relatively movable coned pulley sections on each shaft; for each movable coned pulley section and operatively connected therewith, a separate cylinder containing fluid under pressure, and a piston movable in the cylinder and means, exerting a longitudinal stress on the shafts and permitting rotation thereof, for effecting simultaneous inverse relative movements between the pulley sections on the shafts comprising means for varying simultaneously and inversely the volumes of fluid in the cylinders.
11. In a device for the purpose described, in combination with the two shafts, a pair of relatively movable coned pulley sections on each shaft; for each movable coned pulley section and operatively connected therewith, a separate cylinder containing fluid under pressure and a piston movable in the cylinder and means, exerting a longitudinal stress on the shafts and permitting rotation thereof, for effecting inverse relative movements between the pulley sections on the shafts comprising means for varying inversely the volumes of fluid in the cylinders.
12. In a device for the purpose described, in combination with two shafts, a pair of relatively movable coned pulley sections on each shaft; for each movable coned pulley section and operatively connected therewith, a separate cylinder containing fluid under pressure, and a piston movable in the cylinder and means for effecting simultaneous inverse relative movements between the pulley sections on the shafts comprising means for varying simultaneously and inversely the volumes of fluid in the cylinders.
13. In a device for the purpose described, in combination with the two shafts, a pair of relatively movable coned pulley sections on each shaft; for each movable pulley section and operatively connected therewith a separate cylinder containing fluid under pressure, and a piston movable in the cylinder; means, exerting a longitudinal stress on the shafts, and permitting rotation thereof, for effecting inverse relative movements between the pulley sections on the shafts comprising means for varying inversely the volumes of fluid in the cylinders and members connecting the movable pulley sections with the pistons adapted to sustain, by longitudinal stress the thrust exerted by the inverse relative movement effecting means.
14. In a device for the purpose described, in combination with the two shafts, a pair of relatively movable coned pulley sections on each shaft; for each movable coned pulley section and operatively connected therewith, a separate cylinder containing fluid under pressure, and a piston movable in the cylinder; means, exerting a longitudinal stress on the shafts and permitting rotation thereof, for effecting simultaneous inverse relative movements between the pulley sections on the shafts comprising means for varying simultaneously and inversely the volumes of fluid in the cylinders and members connecting the movable pulley sections with the pistons adapted to sustain, by longitudinal stress the thrust exerted by the inverse relative movement effecting means.
15. In a device for the purpose described, in combination with the two shafts, a pair of relatively movable coned pulley sections on each shaft; for each movable coned pulley section and operatively connected therewith, a separate cylinder containing fluid under pressure and a piston movable in the cylinder; means for effecting inverse relative movements between the pulley sections on the shafts comprising means for varying 130

inversely the volumes of fluid in the cylinders and members connecting the movable pulley sections with the pistons adapted to sustain, by longitudinal stress the thrust exerted by the inverse relative movement effecting means.

16. In a device for the purpose described, in combination with the two shafts, a pair of relatively movable coned pulley sections 10 on each shaft; for each movable coned pulley section and operatively connected therewith a separate cylinder containing fluid under pressure and a piston movable in the

cylinder; means for effecting simultaneous inverse relative movements between the pulley sections on the shafts comprising means for varying simultaneously and inversely the volumes of fluid in the cylinders and members connecting the movable pulley sections with the pistons adapted to sustain, by longitudinal stress the thrust exerted by the inverse relative movement effecting means. 15 20
